FIRE CONTROL INSTRUMENT

Frank Kowalski, Jr., United States Army,
Carthage, N. Y.

Application October 16, 1941, Serial No. 415,246

10 Claims. (Cl. 33—66)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a method and means for indirect fire of guns, particularly machine guns, although the invention is adapted for the indirect firing of any size or type of gun.

Briefly the method comprises sighting on gun and target from the observation point, laying off distances on these lines of sight proportional to their respective ranges and then determining the elevation, direction and length of the line joining the extremities of the laid-off distances, these readings yielding the necessary data at the gun itself.

The instrument is essentially a plotting board in three dimensions. The one shown by way of illustration is simple, compact and sturdy and will automatically and accurately obtain the three elements of indirect fire, namely, deflection, angle of site, and range from gun to target. Having obtained the range from observation point to gun and observation point to target with a range finder, the three elements of indirect fire are obtained automatically, without further data or computation by sighting the instrument from the observation point to the gun and from the observation point to the target.

It is therefore among the objects of the invention to provide an improved method of obtaining the elements necessary for indirect fire and to provide an instrument of novel features for obtaining such elements.

The specific nature of the invention as well as other objects and advantages thereof will clearly appear from a description of a preferred embodiment as shown in the accompanying drawing in which:

Figure 1 is a view of the instrument in elevation.

Figure 2 is a top plan view.

Figure 3 is a diagram showing the locations of the gun, target and observation point.

Figure 4 is a sectional view taken on the line 4—4 of Figure 2, and

Figure 5 is a sectional view taken on the line 5—5 of Figure 2.

Figure 6 is a section taken on the line 6—6 of Figure 1.

Referring to the drawing by characters of reference, there is shown the head of a tripod or other supporting structure 1 for mounting an upright shaft 2. Rotatively carried by the shaft 2 is a collar 3 and this collar carries a horizontal

5 arm 4, an upright 5 and an arm 6 pivoted at 7 on the upright 5. Collar 3 and hence arm 4 and its system are rotated about upright shaft 2 by means of a worm 8. Shaft 2 is held against rotation by means of a locking lever 9. Upright 5 together with arm 6 is rotatable with respect to arm 4 by means of a worm 10. A locking device for the worm gearing is shown at 11. The base 12, housing the gearing 10 and holding upright 5 is 10 slidable along arm 4 and locked in position by a set screw 13. Hinged arm 6 is elevated or lowered by means of a threaded nipple 14 carried by a projection 15 on the upright 5.

15 Arm 16 is hinged at 17 to a cap 18 rotatively seated on a sleeve 19 which in turn is received on a threaded portion 20 of the shaft 2. The sleeve 19 when rotated will lift or lower the cap 18 and hence the arm 16. A nipple 21 serves to swing the arm 16 about its pivot 17. A set screw 22 20 locks the cap 18 in position, and sleeve 19 is locked by means of a slotted section 23 and a bolt 24. A peep sight 25 is independently rotatable on a projection 18' of the cap 18.

25 Upright 5 carries a front sight 26 and arm 16 carries another front sight 27.

The arms 6 and 16 have opposed thin edges 28 and 29 respectively and the sloping sides of the arms near the thin edges bear graduation marks. Arm 4 is likewise graduated to the same scale as arms 6 and 16.

30 The perpendicular distance from the top of front sight 26 to the upper edge 28 of arm 6 is the same as the perpendicular distances from the top of front sight 27 and from the center of peep sight 25 to the bottom edge 29 of arm 16. Preferably pivot 7 will lie in the line of the top edge 28 of arm 6 and pivot 17 will lie in the line of the bottom edge 29 of arm 16, although the pivots may be located centrally of the arms in view of the small errors involved. Thus the line of edge 28 will always be approximately parallel to the plane determined by the three sights. The parallelism is not strict for the reason that front sight 27 is not always vertical as are the other two sights. It could be made so, as for instance by a universal mounting and counterweight for the sight, but if the elevations are not excessive and if the height of sight 27 above lower edge 29 is minimized, the errors will be negligible.

35 It will now be evident that arms 6 and 16 may be varied in azimuth and elevation and that the rear sight 25 may be raised and lowered as well as rotated. In addition, the upright 5 may be moved to and from the rear sight.

Operation

To operate the instrument, upright 5 is moved to a position on arm 4 such that the distance from front sight 26 to rear sight 25 is proportional to the range from observation point to gun. The front sight 26 is next brought into the direction of the gun by rotating arm 4 with worm 8 and is then lined directly on the gun by raising or lowering rear sight 25 with sleeve 19 and then clamping the same with bolt 24. The instrument is now fixed as to range, direction and elevation of the line, observation point, to gun. Set screw 22 is now loosened and cap 18 together with arm 16 is rotated until front sight 27 is lined through the rear sight 25 on the target as to direction. With nipple 21, arm 16 is raised or lowered until front sight 27 is lined through the rear sight onto the target as to elevation. The instrument is now fixed as to direction and elevation of the line, observation point to target.

With rotating mechanism 10 and elevating nipple 14, the upper edge 28 of arm 6 is brought into contact with the lower edge 29 of arm 16 at a point on edge 29 distant from rear sight 25 an amount proportional to the range, observation point to target.

Since the rear sight 25 is freely rotatable, the lines, observation point to gun and observation point to target may be rechecked.

The angle on drum 12 gives the angle at the gun position from observation point to target. The range on arm 6 is proportional to the range from gun to target. The graduations may be such that the range is read directly. A clinometer placed on edge 28 of arm 6 will give the angle of site from gun to target. Arm 6 may also be graduated in mils so that instead of reading the range from gun to target, the angle of elevation in mils for the range from gun to target may be read directly thus obviating the need for reference to a range table.

In the diagram of Figure 3, O represents the rear sight, G the gun position and T the target. G' is the position of the front sight 26 and T' is a point directly above the intersection of edges 28 and 29 on the line, observation point to target. Since the sides are respectively proportional and include a common angle the triangles are congruent and therefore G'T' is proportional to GT and angle OG'T' is equal to angle OGT. Furthermore since parallel lines make equal angles with their projections on a plane, the clinometer reading on the edge 28 of the arm 6 (which, as shown above, is parallel to the plane of OGT) gives the same angle with the horizontal as GT, or angle of site of the line GT.

By incorporating a compass in the instrument it may be employed in a problem involving multiple observation points. In the case where there is no convenient observation point from which both gun and target can be seen, the instrument is employed first at a point commanding the gun and then at a point commanding the target. In this case the instrument is employed first to determine the range, angle of site and azimuth of the line from gun to second observation point. This will furnish the data for setting the line through peep sight 25 and sight 26 on the gun position, although the latter cannot be seen from the second observation point. The compass may be carried either on the drum under the shaft 5 or on the shaft under the peep sight 25. As shown, a compass 50 is carried on the drum concentric with the shaft 5 and contains a float 51 having a magnetic needle and dial whose North

point is identical at 52. A pointer 53 on shaft 5 will indicate the azimuth thereof on said dial. After the sights of arm 4 have been aligned on the invisible gun the sights of arm 16 are trained on the target and the data from gun to target determined in the usual manner as from a single observation point.

The proper elevation from second observation point to gun is conveniently obtained by swinging sight 27 alongside sight 26, setting arm 16 with a clinometer and then adjusting peep sight 25. Clinometers may be permanently installed in arms 6 and 16.

Some advantages of the invention may be summarized as follows:

The new instrument replaces plane table, pencil, protractor, range table and aiming circle thus offering considerable improvement as to simplicity, weight and bulk. Fewer readings are necessary thus lessening the chance for personal error. No formulas are necessary to compute the angle of site and the elements of fire are obtained as fast as an aiming circle can obtain the bare data. Errors of arithmetic and algebra are obviated. The instrument is simple in principle and the method is readily taught. Firing problems can be worked in any kind of weather, and shelter is not required as is often the case when a plane table is used. Since the instrument is automatic, a probable error could be computed from it, and correction made by searching and traversing the gun within the limits of the probable error.

I claim:

35. 1. A fire control apparatus comprising a mounting, a rear sight freely rotatable in azimuth thereon, a pair of arms extending laterally from said mounting and independently rotatable about a vertical line through said rear sight, a front sight on each of said arms, and a third arm carried by one of said arms and adapted to intersect the angle between the pairs of arms.

45. 2. A fire control apparatus comprising a mounting, a rear sight freely rotatable in azimuth thereon, a pair of arms extending laterally from said mounting and independently rotatable about a vertical line through said rear sight, one of said arms being mounted for swinging motion in a vertical plane about a point in said vertical line through said rear sight, and a front sight on each of said arms.

55. 3. A fire control apparatus comprising a mounting, a rear sight freely rotatable in azimuth thereon, a pair of arms having front sights extending laterally from said mounting and independently rotatable about a vertical line through said rear sight, one of said arms being mounted for swinging motion in a vertical plane about a point in said vertical line through said rear sight, and an arm on the other of said arms mounted for swinging motion about a point in a vertical line through the front sight thereof and being rotatable in azimuth about said line.

60. 4. In a fire control apparatus as in claim 3, means for varying the radial position of the front sight on the second mentioned of said arms.

5. In a fire control apparatus as in claim 3, means for adjusting the angle of elevation of the first mentioned of said arms and of the third mentioned arm, respectively.

6. A fire control apparatus comprising a mounting, a vertical shaft on said mounting, an arm on said shaft extending laterally therefrom and rotatable thereabout, an assembly having an upright member and mounted on said arm for

sliding motion thereon, means for rotating said upright, a front sight on said upright, a second arm extending from said upright and mounted for swinging motion in a vertical plane about a point in a vertical line through said front sight, means for varying the angle of elevation of said second arm, a third arm and holding means therefor mounted on said vertical shaft for rotation thereabout, a rear sight mounted for independent rotation on said holding means, means for raising and lowering said holding means and rear sight, a third arm carried by said holding means, extending laterally therefrom and mounted for swinging motion in a vertical plane about a point in a vertical line through said rear sight, means for varying the angle of elevation of said third arm, a front sight on said third arm, said second and third arms being so constructed and arranged that when crossed and in contact, one edge of said second arm is parallel to the plane of the three sights.

7. A fire control apparatus comprising a mounting, a rear sight freely rotatable in azimuth thereon, a pair of arms having front sights extending laterally from said mounting and independently rotatable about a vertical line through said rear sight, one of said arms being mounted for swinging motion in a vertical plane

about a point in said vertical line through said rear sight, an arm on the other of said arms mounted for swinging motion about a point in a vertical line through the front sight thereof and being rotatable in azimuth about said line, and a compass concentric with one of said vertical lines.

8. A fire control apparatus comprising a mounting, a rear sight freely rotatable in azimuth thereon, a pair of arms extending laterally from said mounting and independently rotatable about a vertical line through said rear sight, one of said arms being mounted for swinging motion in a vertical plane about a point in said vertical line through said rear sight, a front sight on each of said arms, and a compass concentric with the sight on the other of said arms.

9. An angle and distance measuring instrument comprising a mounting, a rear sight thereon, a pair of arms rotatable on and about said mounting, one of said arms being universally mounted, and a third arm universally mounted on the other of said pair of arms, and adapted to contact the first-named universally mounted arm.

10. In an instrument as in claim 9, means to adjust the vertical angle of said universally mounted arms, respectively.
